ADJUSTABLE HAND-STOP FOR FIREARMS

Robert J. McFeeter, Bloomfield, N.J.

Application November 4, 1957, Serial No. 694,386

3 Claims. (Cl. 42—85)

My invention relates to firearms and more particularly to an adjustable hand-stop for rifle-type firearms.

Contemporary hand-stops, or hand abutments, are either fixed adjacent the forward end of the firearm, or are adjustable fixed longitudinally of the elongated barrel of the rifle. In the use of firearms employing such a hand-stop, the marksman's hand, which is used to support the forward end of the firearm, normally abuts the hand-stop along the side of the index finger adjacent the knuckle thereof. It is customary for the marksman to press forward with this hand, particularly when a sling-strap is used. The resultant pressure on the hand is uncomfortable and painful.

Marksmen sometimes attempt to alleviate such pain by turning their hand about the rifle forestock, to an unnatural position wherein the marksman's hand abuts the hand-stop at the web between the thumb and forefinger. This, however, creates a strain on the wrist and results in the hand being out of alignment with the marksman's forearm.

The above-referred to discomforts are eliminated with the hand-stop of my invention, which is adjustable transversely of the rifle and may, therefore, be positioned to provide a comfortable rest for the marksman's hand. The marksman is thereby able to grasp the rifle in a natural manner, without straining the wrist, and without the discomfort of pressure on the forefinger joint.

Obviously, the accuracy with which the marksman is capable of performing is greatly enhanced when the rifle is grasped in a natural, comfortable position.

An object of this invention is the provision of a firearm having a hand-stop which eliminates the discomforts mentioned above.

An object of this invention is the provision of a fire-arm hand-stop which is adjustable transversely of the forestock of an elongated barrel type firearm to a position to provide a comfortable rest for the marksman's hand.

An object of this invention is the provision of an adjustable hand-stop, or abutment, the position of which may be adjusted transversely of the forestock of an elongated barrel type firearm to adapt the firearm to the user's physical characteristics.

An object of this invention is the provision of a pivotally-mounted hand-stop for an elongated barrel type firearm which may be pivoted to either side of the longitudinal center of the firearm.

An object of this invention is the provision of a slidably-mounted hand-stop for an elongated barrel type firearm which may be slidably positioned laterally of the longitudinal center of the firearm.

These and other objects and advantages will become apparent from the following description when taken with the accompanying drawings. It will be understood that the drawings are for purposes of illustration and are not to be construed as defining the scope or limits of the invention, reference being had for the latter purposes to the appended claims.

2

In the drawings wherein like reference characters denote like parts in the several views:

Figure 1 is a perspective view showing a firearm embodying my novel hand-stop in use;

5 Figure 2 is a fragmentary longitudinal sectional view of the fore-end of a firearm showing my adjustable hand-stop attached thereto;

Figure 3 is a top plan view of the hand-stop removed from the firearm;

10 Figure 4 is a fragmentary bottom view of the fore-end of the firearm showing the marksman's hand grasping the forestock in abutting relation with the laterally displaced hand-stop;

15 Figure 5 is a fragmentary longitudinal sectional view of the fore-end of a firearm showing a modified form of hand-stop embodying my invention; and

Figure 6 is a top plan view of the hand-stop shown in Figure 5 and removed from the firearm.

Reference is first made to Figure 1 of the drawings, 20 wherein the firearm shown comprises a barrel 10, having a forestock 11 mounted on the under side thereof. The forestock may be integrally formed with the buttstock 12.

A sling-strap 13 of a type well known to those skilled 25 in this art, is suitably secured to the firearm and is provided with a looped-portion 14 which extends about the marksman's arm above the elbow. In the normal shooting position, the marksman flexes this arm thereby tensioning the sling-strap 13. This action, with a properly adjusted sling-strap, results in firmly abutting the marksman's hand 16 against my novel hand-stop 17 mounted 30 on the bottom of the forestock 11.

As mentioned above, contemporary hand-stops are positioned in a vertical plane extending through the longitudinal center of the firearm whereby the marksman's 35 hand 16 abuts the hand-stop 17 on, or adjacent, the knuckle of the index finger, when the rifle is grasped in a natural manner, causing much discomfort. The hand-stop 17 of my invention is adjustable laterally of the rifle longitudinal center whereby the hand 16 naturally, and 40 comfortably, abuts the hand-stop 17 at the web of the hand between the thumb and forefinger.

Reference is now made to Figure 2 of the drawings, 45 wherein there is shown a longitudinal sectional view of the hand-stop 17 attached to the forestock 11. (In Figure 2, the hand-stop is shown in longitudinal alignment with the firearm for clarity of illustration.) An anchor plate 18 is shown embedded in the forestock 11 with the lower surface thereof flush with the bottom surface of the forestock.

The anchor plate 18 is secured to the 50 forestock 11 by bolts 19 which extend through countersunk holes adjacent the forward and rear ends of the anchor plate. Nuts 21 are threaded to the bolts 19, and seat within recesses in the upper surface of the forestock 11. The anchor plate 18 is formed within a plurality 55 of threaded holes 22 evenly spaced longitudinally thereof.

Reference is now also made to Figure 3 of the drawings for a description of my novel adjustable hand-stop. The hand-stop 17 includes a base-plate 23 which is securely attached to the anchor plate 18 by means of an attaching bolt 24 which threadedly engages one of the holes 22.

The base-plate 23 is provided with a generally cylindrical-shaped lug, or pin, 26 integrally formed therewith and which is adapted to engage a hole 22 in the anchor plate rearwardly of the hand-stop attaching screw 24. The 65 attaching screw 24, together with the pin 26, provide means for securely attaching the base-plate 23 to the anchor plate 18. It will be apparent that the base plate may be attached at any desired longitudinal position along the anchor plate within the range of adjacent holes 22 70 in the anchor plate.

The lower face of the base-plate 23 is provided with a

plurality of teeth members 27 located radially of the hole therein through which the attaching screw 24 extends.

The teeth 27 cooperate with a plurality of similarly-shaped teeth members 27' radially positioned on the upper face of an arm member 28 adjacent the end thereof. The attaching bolt 24 extends through holes in the arm member 28 and base-plate 23 which are centrally positioned of the cooperating teeth members 27, 27'. By loosening the attaching bolt 24 sufficiently, the teeth members 27, 27' may be disengaged, and the arm member 28 pivoted about the attaching bolt to any position desired.

A generally cylindrical-shaped hand-stop member 29 is secured to the arm member 28 at the end opposite the attaching screw 24 by means of a bolt 31 which engages a threaded hole in the arm member. The bolt 31 extends, also, through a generally cylindrical-shaped loop base member 32 to which a sling-strap attaching loop 33 is pivotally secured; the forward end of the sling-strap 13 being shown looped through the said loop member 33.

The cylindrically-shaped hand-stop member 29 is provided with a semi-cylindrical, axially-extending, flange 29' on the upper face thereof against which the marksman's hand abuts in use. It will be apparent, that by loosening the attaching screw 24 a sufficient amount, the hand-stop member 29, which is secured to the arm member 28, may be rotated about the attaching screw 24 to any desired position, and relocked in place by retightening of the bolt 24, with the teeth members 27, 27' in cooperating relation. Thus, the hand-stop member 29 may be swung to either side of the vertical plane through the longitudinal center of the firearm.

Reference is now made to Figure 4 of the drawings, wherein there is shown a fragmentary bottom view of the rifle forestock 11 with the marksman's hand 16 in abutting relation with my novel adjustable hand-stop device. As viewed in Figure 4, the hand-stop member 29 is pivoted counterclock-wise about the attaching bolt 24 from a central position along the longitudinal axis of the firearm, rearwardly of the attaching bolt. In the position shown, the hand-stop is adjustably-positioned for use by a right-handed marksman. With the hand grasping the forestock in a natural and comfortable manner, the forward pressure of the hand on the hand-stop member is located on the web of the hand between the thumb and forefinger. Unlike conventional, centrally-positioned hand-stop members, no direct pressure is made to bear on the bones and joints of the forefingers when the hand-stop member is properly positioned on the firearm. With one or two trials, the marksman may determine the correct position for maximum comfort. The marksman's hand may be maintained in line with his forearm for a comfortable grip, thereby relieving any bending strain resulting from an unnatural grasp of the forestock required to place the web between the thumb and forefinger on the hand-stop of a conventional type, centrally-positioned, hand-stop. The hand-stop may be swung to either side of the vertical, longitudinal, center plane of the firearm, and adjustably positioned, for use by either right or left-handed marksmen.

Reference is now made to Figures 5 and 6 of the drawings, wherein a modified form of laterally adjustable hand-stop for a firearm is shown. The hand-stop device therein shown, designated generally by the reference numeral 36, is shown attached to an anchor-plate 18 of the type shown in Figures 2 and 4. The hand-stop device comprises a base-plate 37 which is attached to the anchor-plate 18 by means of an attaching bolt 38 extending through a counter-sunk hole in the base-plate and threadedly engaging one of the holes 22. The integrally-formed pin 26 on the base-plate is adapted to engage an adjacent hole 22 in the anchor-plate. The lower face of the base-plate 37 is provided with a dove-tail tongue member 39 integrally formed therewith, as seen in Figure 5. The tongue member, as seen in Figure 6, is provided with a laterally extending portion 39'. A generally cylindrical-

shaped hand-stop member 41 is provided with a dove-tail-shaped groove 42 in the upper face thereof within which the tongue member 39 slidably fits.

A kerf, or slot, 43 is formed across the hand-stop member 41 longitudinally of the groove 42 along the center thereof. A hole 44 is formed transversely of the slot 43, from the forward face of the hand-stop member 41, which hole extends past the slot. The portion of the hole to the rear of the slot 43 (to the right, as viewed in Figures 5 and 6) is threaded, and receives a locking bolt 46. The hand-stop member 41 is secured to the tongue member 39 on the base-plate 37 by tightening of the locking bolt 46. The loop base member 32, with the loop 33 pivotally attached thereto, is bolted to the bottom of the hand-stop member 41.

It will be apparent that the hand-stop member 41 of Figures 5 and 6 is adjustably positioned transversely of the longitudinal center of the rifle after first loosening the locking bolt 46. In the form of the hand-stop device shown in Figures 5 and 6, the extending portion 39' of the tongue member 39 extends to the right of the longitudinal center of the rifle, to a point adjacent one end of the dove-tail slot 42. Since the tongue member 39, with the extending portion 39' must not ordinarily extend beyond the edge of the hand-stop member 41, but instead, must remain within the dove-tail groove 42, the hand-stop member 41 is adapted to be adjustably positioned only to the right of the rifle longitudinal center. The hand-stop device of Figures 5 and 6 is, therefore, designed for use by a left-handed marksman, only. Obviously, if the hand-stop device was for use by right-handed marksmen, a base-plate 37, having a dove-tail tongue member 39 which extends to the left of the rifle longitudinal center could be used. As with the hand-stop device of Figures 1-4, the hand-stop of Figures 5 and 6 is adjustable by trial and error to provide a comfortable grip for the marksman.

It will be apparent that the extending portion 39' of the hand-stop device of Figures 5 and 6 could be completely deleted from the structure and, in this way, the hand-stop member 41 made adjustable to either side of the longitudinal center of the rifle. Further, it will be understood by those skilled in this art, that since the type of anchor plate 18 which is employed in rifles of different manufacturers varies in design, the base-plates 23 and 37 shown in the drawings, may be modified for suitably mounting the same on such modified anchor plates.

Having now described my invention in detail in accordance with the Patent Statutes, various other changes and modifications will suggest themselves to those skilled in this art, and it is intended that such changes and modifications shall fall within the spirit and scope of the invention as recited in the following claims.

I claim:

1. An adjustable hand-stop for use on a fore-end of a firearm, said hand-stop comprising a base plate adapted to be supported on the fore-end, means forming a plurality of radially-extending teeth members on the lower surface of the said base plate, an arm member having a plurality of radially-extending teeth members formed thereon and adapted for cooperation with the said teeth members on the base member, means releasably securing the said arm member to the said base plate with the cooperating teeth members thereon in engaging relation, and a hand-stop member secured to the said arm member, the said hand-stop member being positionable transversely of the said fore-end.

2. An adjustable hand-stop for use on the forestock of a firearm, said hand-stop comprising a base plate adapted to be supported on said forestock, an arm member, complementary interengaging means on the lower surface of said base plate and on said arm member, allowing movement of said arm member relative to said base plate transversely of the forestock, means releasably securing the said arm member to the said base plate with the inter-

engaging means in engaged relation, and a hand-stop member secured to said arm member and thereby positionable transversely of said forestock.

3. An adjustable hand-stop for use on the forestock of a firearm, said hand-stop comprising a base plate adapted to be supported on said forestock, a hand-stop member, tongue and groove elements allowing sliding of said hand-stop member with respect to said base plate transversely of said forestock, one of said relatively-slidable members carrying the tongue element and the other the cooperating groove element, and means releasably securing said

hand-stop member in transversely adjusted position with respect to said base plate.
